UNITED STATES PATENT OFFICE.

WILLIAM A. LOCKARD, OF PHILADELPHIA, PENNSYLVANIA, ASSIGNOR OF ONE-HALF
TO ARTHUR E. STANGE, OF PHILADELPHIA, PENNSYLVANIA.

RAILWAY-TIE AND FASTENER.

1,181,904.

Specification of Letters Patent.

Patented May 2, 1916.

Application filed March 6, 1916. Serial No. 82,477.

To all whom it may concern:

Be it known that I, WILLIAM A. LOCKARD, a citizen of the United States, residing at Philadelphia, in the county of Philadelphia 5 and State of Pennsylvania, have invented certain new and useful Improvements in Railway-Ties and Fasteners; and I do declare the following to be a full, clear, and exact description of the invention, such as 10 will enable others skilled in the art to which it appertains to make and use the same.

My invention relates to railway ties and fasteners and has for its object to improve upon the construction shown in my U. S. 15 Patent No. 1,187,990, the improvements residing in certain novel features of construction and in new combinations of parts to be hereinafter fully described and claimed, the descriptive matter being supplemented by 20 the accompanying drawing which constitutes a part of this application and in which:

Figure 1 is a top plan view of the invention showing its application at the meeting ends of two rails; Fig. 2 is a longitudinal 25 sectional view taken on the plane of the line 2-2 of Fig. 1; Figs. 3 and 4 are vertical transverse sections taken respectively on the planes indicated by the lines 3-3 and 4-4 of Fig. 1; Fig. 5 is a horizontal section taken 30 on the plane of the line 5-5 of Fig. 2; Fig. 6 is a transverse section showing a slightly modified form of construction employed when two rails of unequal size are to be joined at one end of the tie.

35 In specifically describing the construction shown in the drawings above briefly described, similar characters are placed on corresponding parts throughout the several views and reference is herein made to the 40 numerous elements by their respective indices. To this end, the numeral 1 designates the tie proper which is constructed of a single length of channel iron or steel, the bottom 2 of said tie being roughened by the 45 provision of a plurality of transverse V-shaped grooves 3 whereby to assist in holding the device against longitudinal shifting transversely of the railway. The tie is also held against movement in this manner by 50 the thrust plates 4 which are secured between the ends of side flanges 5 as shown clearly in Figs. 1 and 2, the lower edges of these plates being spaced from the bottom 2 in order that water which would otherwise collect in the tie may drain therefrom.

In use, the entire tie is embedded in the roadbed as indicated in Fig. 2, whereupon the side flanges 5 and the thrust plates 4 will prevent shifting of said tie in either direction. Adjacent one end, the flanges 5 have notches 6 formed in their upper edges, each of said notches having an undercut angular end wall 7 and another straight inclined wall 7^a. The walls 7 are disposed on a line extending at strictly right angles to the length of the tie, while the walls 7^a are alined obliquely of said tie as clearly shown in Fig. 1. This arrangement is essential for reasons to be clearly set forth. Spanning the gap between the side flanges 5 and resting on the bottoms of the notches 6, 50 is a transverse rail supporting plate 8 having downturned ends 9 which abut the outer sides of the aforesaid flanges 5 to hold said plate against endwise shifting. One of the rails R is adapted to rest on the plate 8 in contact with the ends 7 of the notches 6, which ends constitute abutments for preventing lateral shifting of said rail in one direction. To hold the rail in this position, 55 a flat wedge 10 is driven between said rail and the end walls 7^a, said wedge having a slot 11 adjacent one end approximately alining with a slot 12 adjacent one edge of the plate 8. An upright wedge 13 is driven 60 downwardly through the slots 11 and 12 with its outer edge in contact with the inner side of one flange 5, this wedge 13 therefore serving to forcibly move the wedge 10 to 65 operative position and hold it in this position. The lower end of the wedge 13 is provided with a vertical slot 14 positioned below the plate 8, said slot receiving a third and locking wedge 15 formed of a single 70 strip of metal bent upon itself into the shape of a cotter pin, whereby after this wedge is driven to hold the wedge 13 in operative 75 position, its arms may be bent laterally to prevent removal until desired.

The fastening means just described operates to advantage when used between the ends of a rail, but when one end of a tie is to be disposed beneath the meeting ends of a pair of rails, slightly different construction is necessary. This construction is shown 80 at the opposite end of the tie from that above described and consists of a pair of notches 6^a alined obliquely of the tie, a supporting plate 8^a extending between said notches and having downturned ends 9^a and 110

a pair of wedges 10^a driven between the opposite end walls of the notches 6^a and the opposite sides of the meeting ends of the two rails, said wedges 10^a being held in position by upright wedges 13^a driven through slots therein and through other slots in the plate 8^a, the last named wedges being in turn locked by wedges 15^a, all of this construction being very similar to that above described.

10 The two wedges 10^a have upstanding flanges 16 which abut the webs of the rails and serve as fish plates, bolts 17 being passed through these flanges and through said webs as shown. The inner faces of the 15 flanges 16 are grooved longitudinally at 16^a to receive the usual bonds which connect the meeting ends of the rails if the latter be used on electric railways. This construction protects said bonds and not only prevents 20 accidental dislocation thereof, but will overcome any possibility of the bonds being stolen to be sold as now often occurs, since these bonds are constructed of rather precious metal. The wedges 10^a having the 25 flanges 16 are used only when one end of the tie is positioned beneath a joint and rail. Under other circumstances, that is, when the notches 6^a receive the intermediate portions of rails, strictly flat wedges identical 30 with that disclosed at 10 are used, further description of these wedges being deemed unnecessary.

In Fig. 6 a slightly modified form of construction is shown, in which one end of the 35 rail supporting plate 8^b is offset vertically from the other end, this being done in order that the meeting ends of for instance an eighty pound and a hundred pound rail may be effectively connected.

40 By constructing the tie and fastener in the manner above described, it will be highly efficient and durable, particular emphasis being laid upon the fastening means shown since this has been found to produce 45 good results and to rigidly hold the rails against creeping, it being obvious that an enormous amount of clamping action can be obtained by the arrangement of wedges shown. Furthermore, by constructing the 50 device as shown and described, differently shaped ties need not be used where joints are to be made in the rails, since one end of the improved tie is constructed to allow it to serve as such a joint.

55 In conclusion, I will state that although certain specific details have been shown and described for accomplishing probably the best results, numerous changes may be made within the scope of the invention as 60 claimed without sacrificing the main advantages thereof.

I claim:

1. A railway tie having spaced abutments

to loosely receive a rail therebetween, a horizontal wedge to be disposed between the 65 rail and one of said abutments, said wedge having a slot opening through its upper and lower faces, and an upright wedge adapted to be driven through said slot to move said horizontal wedge to operative 70 position, the tie having a fixed portion against which said upright wedge may thrust.

2. A railway tie having spaced abutments to loosely receive a rail therebetween, a 75 horizontal wedge to be disposed between the rail and one of said abutments, said wedge having a slot opening through its upper and lower faces, an upright wedge to be driven through the slot to move said 80 horizontal wedge to operative position, said upright wedge also having a slot, and a locking wedge to be driven horizontally through the last named slot to hold said upright wedge in operative position. 85

3. A channel-shaped tie, a transverse plate spanning the gap between the side flanges of said tie, said flanges having abutments adjacent one side edge of the plate, and the latter having adjacent its 90 edge a slot, means adjacent the opposite edge of said plate to abut a rail, a horizontal wedge to rest on said plate between the abutments and rail for holding the latter, said wedge having a slot opening through 95 its upper and lower sides, and an upright wedge to be driven downwardly through the slots in the wedge and plate to move the former to operative position.

4. A channel-shaped tie, a transverse 100 horizontal plate spanning the gap between the side flanges of said tie, said flanges having abutments adjacent one side edge of the plate, and the latter having adjacent its 105 edge a slot, means adjacent the opposite edge of said plate to abut a rail, a horizontal wedge to rest on said plate between the abutments and rail for holding the latter, said wedge having a slot opening through its upper and lower sides, an upright wedge 110 to be driven downwardly through the slots in the wedge and plate to move the former to operative position, said upright wedge also having a slot to be disposed below the plate, and a horizontal locking wedge to be 115 driven through the last named slot in contact with the under side of said plate to hold said upright wedge in operative position.

In testimony whereof I have hereunto 120 set my hand in presence of two subscribing witnesses.

WILLIAM A. LOCKARD.
